FOUNDATION GARMENT

Arthur Goldstein, New York, N. Y., assignor to Tru Balance Corsets, Inc., New York, N. Y., a corporation of New York

Application August 6, 1953, Serial No. 372,792

5 Claims. (Cl. 2—37)

This invention relates to undergarments; more particularly to foundation garments and corsets.

This invention relates to improvements in undergarments of the type shown in my Patent No. 2,304,812, December 15, 1942.

In my patent aforesaid efforts were made by me to provide a posture corrective device in an undergarment generally referred to as a corset or foundation garment. In these constructions, the objective was to provide an arrangement of elastic pull of the segments of the garment which would work in harmony with the muscles and ligament structure of the body, tending to correct the posture, and effective during activity of the wearer, and which comprised side members and hip members, acting as described against a central inelastic front member located in relation to each other so that a desirable abdomen moulding influence would be secured. More particularly, in my patent aforesaid, I have endeavored to support a central inelastic front member in oppositely divergent directions, by a two-way stretch material, specifically a warp knit fabric with primary and secondary elasticity of different magnitude providing torsional adjustability of the fabric for carrying out the application of the divergent forces of the elastic side and hip members to each other and to the central member during bodily activity.

I have found that with lack of care in adjustment of the garment, the far greater activity to which the hip members are subjected than are the side members tends to defeat some of the purposes intended by my prior garment construction, resulting in an inadequate abdominal flattening influence. I have also found that to increase the elastic pull to make it more rigorous in the pulling action, results in unnecessary discomfort, due to the restraining influence on movement, to the point that the divergent tension along the natural lines of the body of the side panels is rendered ineffectual properly to mould the abdomen, and that the benefits of my prior construction are lost unless there is unusual care and perfection in locating and maintaining the garment at a critical position. This shortcoming I attribute to the limitation in the corset or foundation garment of my prior construction of the point of positioning of the apex of the side members to provide an appropriate constraining, opposing force to some relatively fixed position, such as the hip members and, thus, the assembly of my prior construction tends to provide largely a lift of the abdomen rather than a conjoint lift and compressive force tending to flatten the same.

While desirable results are, in a measure, secured with the foundation garment of my prior construction by the employment of shoulder straps which form the opposing force to the downwardly directed elastic hip members, in the case of using two-way stretch material, the principle is not desirably applicable without an unusual amount of constraining action and an unduly uncomfortable result to the wearer.

Thus, in accordance with my prior patent aforesem-

2

tioned, the balance of forces along the muscles and ligaments, insofar as supplying a positive corrective device, may be attributable to the pull of shoulder straps in opposition to the oppositely divergent forces of the side members and hip members acting on the front panel, effective where accurate location is practiced by the wearer and a careful fit, in the case of the corselette or partial garment, has been provided.

I have found that by exercising a constraining influence of the elastic members above the hip bone crest and into the waistline to a point where I provide an immobilizing area to the garment with reference to which the downward hip members may act, the usual benefits of my invention are extended to provide a highly desirable flattening influence on the abdomen, a facile and accurate location to secure the desired performance, the ability to use more pliant elastic fabric in the garment panels, especially of the hip members, and the use, with greater latitude of choice, of either one-way or two-way stretch elastic fabric members for the hip or side members.

Thus I have found, and it is an object of my invention to provide, an undergarment in the nature of a foundation garment or corset, employing elastic side members, each having upwardly divergent primary elastic pull, and hip members, each having downwardly divergent primary elastic pull, in relation to an inelastic front member, where the contiguous seam between the side members and hip members follows the groin lines of the wearer to a point above the crest of the hip members and transversely for a distance exerting a transverse pull on the inelastic member above the waistline, the contiguous edges of the side members and hip members providing an immobilizing engaging or anchoring set of points or area, with relation to which the inelastic front member is tautened by the elastic, upwardly directed side members and by the opposed downwardly divergent elastic hip members.

Thus, in accordance with my invention, it is an object thereof, to provide an arrangement of the side panel members and hip members to secure an extended anchorage area adjacent the relatively immovable apex of the os. innominatum or crests of the hip bones and extending into the waistline, whereby to secure ease and accuracy of location of the garment embodying the oppositely divergent elastic side and hip panels, making possible a distribution of the elastic forces, permitting less constraining influence by the active hip members and more intense elastic force transversely on the front member covering a greater portion of the yieldable portions of the body to secure greater abdomen flattening effects, and permitting the use of both one-way stretch and two-way differential stretch materials.

To attain these objects and such further objects as may appear herein, or be hereinafter pointed out, I make reference to the accompanying drawings forming a part hereof, in which—

Figure 1 is a three quarter front perspective view illustrating a garment in accordance with my invention with a portion broken away to show an under layer;

Figure 2 is a section on line 2—2 of Figure 1;

Figure 3 is a three quarter rear perspective view thereof;

Figure 4 is a plan view showing a developed relationship of the various sections entering into the production of the garments illustrated in Figures 1 and 2;

Figures 5, 6 and 7 are, respectively, front, side and rear views of a foundation garment in accordance with another embodiment of my invention.

I now make reference to the drawings, particularly Figures 1 to 4, wherein the garment therein illustrated is in the form of a corset in that there is no attached brassiere. The garment G is provided with a front member

10 of inelastic material, the lower edge 11 of which extends its angular side 12 at an obtuse angle upwardly to the corners 13. The width of the member 10 to either side of the middle along the longitudinal line is sufficient to cover the umbilical region or the visceral cavity or abdomen, preferably extending no wider than the groin adjacent the crest of the pubis and extending vertically upward to the top edge 14 of a size to where the lower ribs would be encountered.

The front member 10 outlines a generally hour-glass configuration or superimposed inverted frusto-triangular members, with the common smaller base defining the points 15, 15 arranged to coincide with the medial portion of the waistline or the break portion of the abdomen in the sitting position.

To a portion of the front member comprising the edges 12, 12 and the segments 16, 16 there are affixed the hip sections 17, 17. The contiguous medial edges of the hip sections 17, 17 are affixed to each other by the medial seam 18 to provide a frontal apron portion below the edges 11 and 12, terminating into the lower edge 18a, along which the usual fastening garters are applied all around the garment.

The hip sections above the side edges 16 are arcuately outlined at their edges 19, 19 to extend inwardly from just above the position of the crests of the ilium X—X and the apices X'—X' of the ossa innominata or hip bones. The corners 20, 20 terminate adjacent the medial side edges 21, 21. The sections 17, 17 and 18 are preferably cut from warp knit elastic fabric in accordance with my patent aforesaid, to have a two-way stretch elasticity, with primary elastic warp threads providing the primary elasticity in a direction diverging downwardly from the medial seam line 18, and more particularly with the primary elastic threads arranged at an angle A of from 10 to 30°, preferably 15°.

In the drawing extending from the indicator 22 is a group of arrows, diagrammatically illustrating the components of forces of elasticity, with the longest component of this group representing the direction of the elastic warp thread where this is employed, as more specifically indicated in my prior patent aforementioned.

To each side of the front member 10, outlined by the sections 23, 23, there are attached the side members 24, 24, with their lower sides contiguous to the groin-contoured diagonal edge 19, previously described, and having their side terminal edges 25, 25 co-terminous with the edge 21. The upper edges 26, 26 extend from the waistline corners 15, 15 rearwardly and upwardly to provide an extended portion over the waistline.

The indicator group of arrows 27 is intended to show diagrammatically the components of elasticity, with the primary elastic warp thread diverging in a direction upwardly from the center line extended from the seam 18 at an angle of from 15 to 45°, preferably 30°. The variation is occasioned by variations in dimensions and proportions of different sizes and shapes of individuals. Above the edges 26 I provide waistline sections 28, 28 each having an edge thereof contiguous with an edge 26 and each attached to the side portions 29, 29 of the front member. The upper terminal edges 30, 30 are co-terminous with the edge 14. The side edges 31, 31 are co-terminous with the edges 21, 25 previously described. The indicator group of arrows 32, 32 diagrammatically show the component of elasticity and the largest component is directed in substantial parallelism with the line indicating the waistline from the corners 15, 15.

To each side of the edges 21, 25 and 31 outlining a vertical side seam, there are attached the edge side panels 33, 33. The edge side panels 33, 33 are made of single way stretch elastic webbing, with the stretch arranged in the direction of the arrows 34, 34, providing no elasticity or stretch in the horizontal direction.

To each side of the edge side panels 33, 33, there are attached the vertically disposed rear side panels 35, 35, ex-

tending from the line along the bottom of the apron to a point co-terminous with the edges 14.

The rear side panels 35, 35 are composed of elastic warp fabric with the primary elasticity shown by the indicator group of arrows 36, 37 varying adjacent the upper edge 14 in a position parallel to the waistline. The indicator group of arrows 37 diagrammatically illustrates the primary elasticity adjacent the lower edge 18a to be downwardly divergent substantially in parallelism with the primary elastic component of the hip members 17.

Between the rear side panels 35, 35 there is positioned the rear panel 38, which has its upper edge 39 adjacent the waistline outlined by the corners 15, 15, previously described. The rear panel 38 is preferably a one-way stretch having its elasticity vertically extended as shown by the arrow 40.

Above the upper edge 39 and between the panels 35, 35, there is affixed a rear waistband panel 41 of two-way stretch material, preferably warp knit elastic fabric of the character employed in the hip panels 17, 17 with the primary elasticity as shown by the indicator 42 extended in a line parallel to the edge 39 and to the waistline.

The assembly as described, in addition to including the features of my patent, as described, has the upper side members not only upwardly divergent with regard to the front panel member to exert its flattening influence on the front member but extends rearwardly over the yielding portions of the waist just above and about the crests of the hip bones or the apex of each of the os innominatum and includes a waistband elastic pull in parallelism to the waistline to provide anchorage for the side members in opposition to the downwardly divergent pull of the hip members 17, 17.

The angular direction of the edges 19, 19 therefore positions the terminal portion of the side members in close relation to the side seam 21 to a point just above the apices of the hip bones at the portions X'—X', but so closely contoured to the same thereby resisting the stress of the downwardly divergent elastic pull of the hip members by the formation of an enveloping hip bone pocket forming an anchorage area. The extension of the side members 24, 24 rearwardly along the waistline and above the seam augments the anchorage tendency along the waistline above the apices of the hip bones X'—X', facilitating the location of the garment as it is drawn by the wearer over the thighs and onto the hips. Further anchorage against the pulling force of the limbs and body in articulation is provided by the side waistline sections 28, 28, held in waistline anchoring position by the rear waistband panel and rear side panels 35, 35. By reasons of the anchorage which is assured adjacent the waistline, the hip members 17, 17 may be made of less intensely elastic fabric, minimizing the constraining influence without loss of moulding qualities.

The combined upwardly divergent pull of the side members 24, 24 and the waistline sections and waistband sections exerts a flattening influence on the front panel 10, requiring no shoulder straps to taunt the front panel in the vertical as well as in the horizontal direction. The firm anchorage afforded by the upwardly divergent, rearwardly elastic side members 24, 24 permits of the intensification of the upwardly divergent elastic pull of these side panel members and for this purpose I may provide a set of subsidiary side members in the under-lay 43, indicated in Figure 2 and shown by the fragmentation of the layer 24 in Figure 1. The under-lay subsidiary side members 43—43 are preferably one-way stretch elastic fabric in which the elastic is stretchable along the lines shown by the arrow 44, so that the elastic threads thereof are in parallelism with the elastic threads indicated by the indicator 27 and running at the same angle to the medial line 18 as the primary elastic of the side members 24.

The under-lay 43 or subsidiary side members of unidirectional reinforcing elasticity augments the side taunting influence on the front panel member, to flatten the

abdomen as well as to intensify the constraining action in the yieldable portions of the body to the upper part of the hip bone and the crest of the ilium, further anchoring the garment to resist the pull of the front hip members. The angular relation of the under-lay subsidiary side members 43-43 does not interfere with the elasticity in parallelism with the waistline in view of the bias position of the fabric with relation to the vertical seams.

In the construction shown, additional locating benefits to augment the upwardly divergent forces of the side members and the downwardly divergent pull of the front hip members is secured by the arrangement of the panel members 33, 35 and 38, it being understood, however, that while the single stretch panel 38 aids in maintaining the proper position of the garment during mobility, where accentuated flattening of the buttocks is desired, the panel 38 may be of indistensible fabric, as in my prior patent.

I may further aid in the proper positioning of the garment with respect to the waistline, at which point the corners 15, 15 are intended to be positioned, by the inclusion of stays, and for this purpose, stays 45, 45, may be included, running from the upper edge 14 to a point co-terminous with the waistline defined by the corners 15, 15. Likewise, I may include stay retaining pockets 46, 46 in each of the edge side panels to keep the garment from rolling and to assure an extended anchorage area being formed by the terminals 25, 25 of the side members 24, 24.

It will likewise be understood that one of the edge side panels 33 may be formed with a separable closure 47, and for this purpose a row of separable fastener elements and actuator may be employed.

While I have shown and described a corset, it will be understood that my invention may be extended to an "all-in-one" type of garment or corselette. For this purpose I refer to Figures 5, 6 and 7, wherein the garment C is illustrated, and in which parts corresponding to parts in the previous embodiment have been given a number one hundred higher.

Here the front panel 110 is formed with hip members 117 and with side members 124, all joined to each other as in the first embodiment. The waistline sections 128, 128, at their upper edges, are joined to the breast cups of the brassiere B, which may be further supported by the shoulder straps 48, 48, running rearwardly to the side edge panels 135, 135 and the rear waistband panel 141. Below the rear waistline panel 141, there is provided the rear panel 138. It is to be observed that in all other respects than the extension to permit the attachment of shoulder straps and brassiere, that the parts 128, 135, 138 and 141, correspond substantially in function and arrangement of the elastic to the waistline section 28, edge side panels 35, rear panel 38, and waistline panel 41.

The efficacy of the anchorage of the "all-in-one" garment to which Figures 5, 6 and 7 refer, is demonstrable by the fact that the foundation garment below the breast cups does not move out of proper position when the shoulder straps 48 are released, and except for the support afforded to the breast cups, the shoulder straps do not offer any material aid in the desirable principles described in connection with the first embodiment.

I have shown and described the front hip members, the side members and the waistline sections in the garments in accordance with the embodiments illustrated which for convenience may be stated to be a multi-stretch fabric, and preferably warp knit elastic fabric of about twenty elastic warp threads to the inch and about sixteen cross ties to the inch, as described in my prior patent, so that the relationship of the elastic fabric to inelastic fabric is to allow for approximately 20 to 30% elongation at the waistline and accordingly I may include the same relationship of elastic to inelastic fabric as described in my patent. It is further to be understood, that while in my prior patent I find it preferable to make use of the said

warp knit elastic fabric to secure a torsional elasticity in the plane parallel to the surface of the fabric and I may therefore secure to a similar extent the benefits thereof in the assembly as described herein. However in view of the features in my improvement herein I may use in the afore-mentioned side members, hip members and the subsidiary under-lay side members, one-way stretch elastic fabric, with the elastic threads arranged in the relative divergent relationship as described for the primary elastic warp threads.

Likewise, it will be understood that while I have shown a garment in which the hip members have the primary elasticity in a downwardly divergent direction and the side members with the elasticity in an upwardly divergent direction with regard to the indistensible front panel member, the construction may be modified to secure the anchorage benefits of the more intense elasticity of the side members and the subsidiary side members under-lay by arranging the front hip members to extend to the waistline as an integral piece, arranging the pattern to cut the same so that the primary portion covering the crests of the ilium and the apices of the ossa innominata is in a downwardly divergent relationship to the edges of the front panel, with a relatively horizontal arrangement of the elastic threads above the line corresponding to the edge 19 up to the waistline, and then applying an under-lay side member corresponding to the under-lay 43 by arranging the primary elastic to provide each of the side member under-lays with an upwardly divergent elastic pull. The under-lays in this particular embodiment are of one-way stretch material, as described in the arrangement in connection with the embodiment illustrated in Figure 1 for the part 43.

In the primary construction employed by me, the hip members and the side members are connected to each other by readily shiftable seams, such as faggoted stitching, so that each of these panels may exercise its independent function without restraint.

While I have shown and described in Figures 5, 6 and 7 an all-in-one type garment without any edge side panels, specifically shown in the first embodiment, it will be understood that such elements, corresponding to the elements 33, may be embodied in the all-in-one construction to provide an insert between the side panels 117, 124, 128 as a front component, and the panel 135 as a rear component, without departing from the essential elements of novelty outlined hereinabove and included within the scope of the appended claims.

Having thus described my invention and illustrated its use, what I claim as new and desire to secure by Letters Patent, is:

1. A foundation garment comprising an inelastic front member adapted to cover substantially the front central portion of the body of a wearer from the waistline and confined at its sides and its lower edge portions to closely adjacent the crests of the pubis and upwardly between the crests of the ilium, thereby substantially to limit the covering of the front member to the groin area, two elastic-fabric side members and two elastic-fabric hip members, each set of said members being fabricated from mixed elastic and inelastic threads, said hip members each being attached to the bottom edge of a side member and with the inner edge thereof to each side of the front member at the lower side and bottom edges thereof and having elastic threads providing the primary elasticity arranged in a direction diverging downward from the sides, the inner edges of each of said side members being attached at one edge thereof to each side of the front member adjacent the upper side portion of said front member, and an another lower edge to a hip member, and the outer edge of each of said side members having its upper terminal edge adapted to extend at the upper end from a line above and conforming substantially along the crest line of the hip bone line of the wearer upwardly and to extend rearwardly to the waistline of the wearer co-

operating with the uppermost corner of the hip member to form a hip bone crest yieldable pocket to constrain the garment substantially immovable downwardly immediately above the hip bone line, and having elastic threads providing elasticity to the front member anchored above the hip bone line and extending from the front member upwardly and rearwardly to the waistline in opposition to the downward pull of the hip members and transversely across the abdomen line of the wearer, the contiguous edge portions of the hip member and side member providing an anchorage area for the downward pull of the hip members, locating the upward pull and transverse elasticity above the line of the apex of the hip bone line.

2. A foundation garment comprising an inelastic front member adapted to cover substantially the front central portion of the body of a wearer from the waistline and confined at its sides to closely adjacent the crests of the pubis and upwardly between the portions covering the crests of the ilium, thereby substantially to limit the covering of the front member to the groin area, two elastic-fabric side members and two elastic-fabric hip members located one below the other, each set of said members being fabricated from mixed elastic and inelastic threads, said hip members each being attached to a lower side and bottom edge portion of each side of the front member at the inner side edges of said hip members and having elastic threads providing the primary elasticity arranged in a direction diverging downwardly from the sides and bottom edge of the front member, and each hip member having an upper, diagonal edge attached to the side member and adapted to follow the groin line of the wearer and transversely rearwardly over the crest of the hip bone line of the wearer, the inner edges of each of said side members each being attached to the upper side portion of the front member and to the upper diagonal edge of the hip member at its lower edge portion and having its upper terminal edge adapted to extend at the opposite end from a line above and conforming substantially along the crest line of the hip bone

- line upwardly and to extend rearwardly to the waistline to constrain the garment substantially immovable downwardly immediately above the hip line elastic stress and having elastic threads providing elasticity to the front member anchored above the hip bone line and extending from the front member upwardly and rearwardly to the waistline in opposition to the downward pull of the hip members and transversely across the abdomen line of the wearer, the contiguous edge portions of the apex of the hip member and side member terminating at and being attached by a common seam to an edge side panel providing an anchorage area for the downward pull of the hip members, locating the upward pull and transverse elasticity above the line of the apex of the hip bone line.
- 15 3. A foundation garment in accordance with claim 1 wherein each of said side members includes subsidiary members providing an under-lay augmenting the side tautening influence on the front panel members.
4. A foundation garment in accordance with claim 1 wherein each of said side members includes subsidiary members providing an under-lay augmenting the side tautening influence on the front panel members comprising one-way stretch elastic fabric, with the elastic threads substantially in parallelism with the elastic threads of the side members.
- 20 5. A foundation garment in accordance with claim 1 wherein each of the side members each have an under-lay augmenting the side tautening influence on the front panel member and comprising elastic fabric in a bias position
- 25 30 with relation to the vertical seams joining the panels to each other.
